UNITED STATES PATENT OFFICE.

THOMAS OSBORNE HOLLAND, OF PHILADELPHIA, PENNSYLVANIA.

COMBINED CARD CASE AND TRAY.

1,126,470.

Specification of Letters Patent.

Patented Jan. 26, 1915.

Application filed September 28, 1904. Serial No. 226,333.

To all whom it may concern:

Be it known that I, THOMAS OSBORNE HOLLAND, citizen of the United States, residing at Philadelphia, in the county of 5 Philadelphia and State of Pennsylvania, have invented new and useful Improvements in Combined Card Cases and Trays, of which the following is a specification.

The object of my invention is to provide 10 a case for individual packs of playing cards which shall also constitute a tray adapted for holding the hands of cards in duplicate whist.

In a case-tray characterized by my invention the following salient and novel points are presented; first, an improved duplicate whist tray is combined with or embodied in a playing card case of ordinary size, and may accompany each individual pack of 20 playing cards; second, the minimum of both bulk and weight is attained for duplicate whist sets of any preferred number of packs, thus providing duplicate whist sets comparatively easy to carry, or to pack as a 25 traveler's companion, or to handle in play at a table; third, the duplicate hands of cards are securely reserved in the order of play with the least physical exertion and without risk of injury to the cards from fastening 30 or other ill adapted holding device; fourth, the combination of a playing card case and of an improved duplicate whist tray is accomplished at a relatively fractional cost.

Generally stated, the invention resides in 35 a playing card case adapted, by means of duplicate hand frame formations in one portion of the case, and corresponding stay-beds in the opposite portion, to separately and relatively receive and hold endwise or 40 sidewise the four hands of cards in duplicate whist.

Instead of incorporating the duplicate hand frame formations in the case-proper, the invention may be carried into effect by 45 means of a separately constructed tray-frame providing the said duplicate hand frame formation and adapted to operate in conjunction with the two halves of the case proper.

50 In the accompanying drawings, forming a part of this specification, and in which like letters of reference indicate corresponding parts, I have illustrated a form of embodiment of my invention, together with modifications, it being understood that other forms of embodiment of the invention may

be employed without departing from the spirit of the same.

In the drawings, Figure 1 is a perspective view of the top portion of my case-tray. Fig. 2 is a perspective view of the body of the case-tray, partly broken away to show the projection, in the bottom, which forms the stay-bed for the card hands. Fig. 3 is a cross section showing a hand of cards 65 in position. Fig. 4 is a perspective view showing a modification, the parts being separated. Fig. 5 is a cross section showing the modified case-tray in use for duplicate whist hands. Fig. 6 is a cross section 70 of my case tray showing a pack of cards incased. Fig. 7 is a view of the case closed, containing a pack of cards, as shown in Figs. 5 and 6. Fig. 8 shows a modified form with the top removed, in which a rectangular, telescopic playing card case is provided with extended sections at the sides and ends adapted to receive the hands of cards. Fig. 9 shows the same in cross section. Fig. 10 shows a modified form in which the cards 80 are arranged transversely, with the top removed. Fig. 11 shows plan view of the cover for the form shown by Fig. 10. Fig. 12 shows a longitudinal cross-section through the assembled case of the modification shown in Figs. 10 and 11. Fig. 13, is a plan view of a modification in which the hands of cards are arranged longitudinally.

Referring to the drawings, A designates the outer section of a telescopic game-card 90 case, which may be constructed of card board, sheet metal, or any such suitable material.

A^2 designates the lower or inner section.

In the top portion of A are four duplicate 95 whist hand frames, a^9 , adapted in size to receive, on their ends, the several hands of cards in duplicate whist. Sufficient margin of cover is left between the edge of the outer section A and the frame formation a^9 , to cover 100 the edge a^{10} of the inner section A^2 , when the two sections are telescoped.

When the case-tray is constructed of card board or like soft fibrous material, the edges of the frame formation a^9 are reinforced to 105 render them serviceable. When the construction is of sheet metal the edges are turned or wired to prevent scuffing of the cards. The hands of cards are retained erectly as shown in Fig. 3 and without danger of the cards sliding out in handling, in the frame formations a^9 with the aid of 110

- registering stay beds a^{11} which are formed in the bottom of the inner section A^2 by means of ribs a^{12} which are sufficiently high to prevent the duplicate card hands slipping centerward in the case-tray. When the case-tray is of card-board construction strips may be secured in proper relative position to the bottom of the inner section A^2 , in lieu of the ribs a^{12} to form the stay-beds a^{11} .
- 10 The space a^{13} , between the ribs a^{12} , may be utilized for the keeping of chips or counters necessary in the game of duplicate whist. The securely erect position of the duplicate hands of cards a^{14} , in the case-tray also permits, without injury to the cards, of placing the case-trays when containing the duplicate hands on top of each other, so that, as will readily be seen, the minimum of table space only will be required for the 8, 12 or 16 sets of hands generally played in the duplicate game.
- 15 The two sections A and A^2 may be reversed, the four duplicate hand frames and beds may be paralleled, in crosswise arrangement, of the case-tray to receive the hands of cards on their ends, or in lengthwise arrangement for receiving the cards on their sides as shown on Figs. 7 and 8 respectively. The invention may also, for further example, be embodied in a form of construction in which a telescopic playing card case may have extended sections on the sides and ends adapted to receive the hands of cards, as shown in Fig. 9.
- 20 As shown in Figs. 8 and 9: "b" designates the extended sections for receiving the four hands of cards, b^1 designating the inner wall of the said sections. In Fig. 10, b^1 designates the bottom of the lower box member, and b^2 designates the strips which form the bed in the bottom to retain erectly on their edges the separate hands of cards. In the cover member b^3 are the apertures b^4 for receiving the said hands.
- 25 In the modified form of construction shown in the drawings bearing the reference marks, A^4 , A^5 and A^6 , which perhaps more perfectly effect a dust proof, and at the same time a neater appearing combination case-tray, A^5 designates a tray-frame which consists of a band or collar A^5 equal in height to the lid or cover member A^4 , and the bottom or cover member A^6 which fit snugly over the said band and form the case proper. The top portion a^{16} of the band a^{15} is provided with card hand receiving formations a^{17} which are adapted to receive the several duplicate whist hands. The lower portion a^{18} of the sheet metal band a^{15} is merely beaded or turned to prevent the sharp edge or corner of the metal from disfiguring the cards when they are put into the case-tray. When employed in the game of duplicate whist sections A^5 and A^6 form the complete

tray, the lower section A^6 being fitted with the inverted grooves A^{12} which form the bed A^{11} registering with the apertures A^{17} .

When the case-tray serves simply to incase a pack of cards a^{21} , the position of the tray-frame A^5 is reversed, the card hand receiving formations a^{17} lying in the bed a^{11} formed by the ribs a^{12} , and the other end a^{18} of the tray-frame projecting above the walls of A^6 to engage the lid A^4 . The wire framework a^{19} , forming the card hand receiving formations a^{17} is secured to the band a^{16} by means of lugs extending therefrom and engaging the wire at its four corners a^{20} a^{20} a^{20} a^{20} . In this separate and adjustable tray-frame construction the card hand receiving formations and the registering bed in the bottom of the case-tray may also be arranged parallel either lengthwise or crosswise of the case-tray, so that the cards may be received on their ends or sides as preferred. The case-tray may have the compass marks, as shown in Fig. 8, or other marks to indicate the order of play, or they may be left blank.

Having thus fully described my invention what I claim as new and desire to secure by Letters Patent of the United States, is:

1. A playing card case comprising a rectangular bottom member adapted to hold a pack of cards, said member having shoulders projected from its base inwardly, a second member adapted to be fitted to the bottom member, said second member having means co-operating with the shoulders in the bottom member for engaging and holding a plurality of cards.

2. A playing card case, comprising a rectangular bottom member adapted to hold a pack of cards, a second member adapted to be fitted to the bottom member, said second member having oblong apertures in its top portion adapted to engage and separately hold, in conjunction with the bottom member, at right angles with the broadsides of the case and to the depth of the case, the four hands of cards in duplicate whist.

3. A playing card case comprising two rectangular telescoping members, one of the said members having compartments at its sides and ends adapted to separately engage and hold, erectly on their edges to the depth of the case, and the four hands of cards in duplicate whist.

4. As an article of manufacture a rectangular band with frames forming apertures extending inwardly at right angles with its walls, and adapted to retain the four hands of cards in duplicate whist.

5. A playing card case comprising two rectangular cover members, and an inner band member, having means to separately engage and hold in combination with the bottom of one of the bottom members, the four hands of cards in duplicate whist.

6. A telescopic playing card case, comprising two rectangular box members, one of which having frames at the edge of its end and side walls, as herein described, adapted 5 to engage and retain the four hands of cards in duplicate whist, one of the said box members being indexed to designate the relative order of the said hands of cards as played.

In testimony whereof I affix my signature, in presence of two subscribing wit- 10 nesses.

THOMAS OSBORNE HOLLAND.
